AUTOMATIC COUPLER FOR MINE CARS

Church G. Humphreys, Volant, Pa.

Application May 22, 1939, Serial No. 275,043

2 Claims. (Cl. 213—178)

This invention relates to couplers for mine cars and the like and has for its principal object to provide a simple yet practical and efficient coupler which may be readily applied to any ordinary car used in mining, excavating, grading and other operations, which is automatically placed in coupling condition, normally latched in such condition and manually releasable at the will of the operator.

The invention consists in the novel general structure and in the particular parts and combinations and arrangements of parts thereof as hereinafter described and set forth in the appended claims, reference being had to the accompanying drawing illustrating a practical adaptation of the invention, in which—

Figure 1 is a top plan view of the fragmentary meeting end portions of two mining cars with the coupler of the present invention applied thereto and in coupling condition;

Figure 2 is a view partly in side elevation and partly in longitudinal section showing the coupling relation of the parts in full lines and other positions of certain parts in broken lines; and

Figure 3 is a view, on a smaller scale, showing a fragmentary portion of one car with the elements of the coupling carried thereby in end elevation.

Referring now to the drawing, the numeral 1 designates a draft extension or platform of one car and 2 a similar extension of the adjoining car, the respective extensions being either directly from the floor or end sill of the car body, or, obviously, from a suitable portion of the underframing or the truck on which the body is mounted. Bolted, as at 3, to the draft extension 1 is a bracket including a longitudinal body plate 4 and a cross member 5 the end portions of which are bolted to the draft extension 1, as at 6, said cross member having an upwardly offset intermediate portion 7 straddling said longitudinal body portion 4. A clevis 8 has a shank portion 9 fitted slidably between the raised portion 7 of the cross member 5 and the adjacent underlying portion of the body plate 4, said shank portion being swiveled on a bolt or pivot stud 10 inserted through aligned apertures in the plate 4, cross member portion 7 and the shank, the bolt or stud 10 being provided with a retaining nut 11 impinging said cross member portion 7. Preferably, the shank 9 of the clevis is of rectangular cross section and of a width somewhat less than that of the distance between the vertical side walls of the raised intermediate portion 7 of the cross member 5 whereby ample space is provided

to permit considerable though limited swinging movement of the clevis on its pivot 10.

Mounted on the clevis 8 to swing laterally therewith but having independent vertically swinging and limited endwise movement thereon is a coupling link 12. As shown, the link 12 is formed with an enlarged circular main body portion 13 and an integral reduced and substantially rectangular bail-like hinge extension 14, the outer transverse part 15 of which is circular in cross section and located in a longitudinally elongated opening 16 provided in the clevis 8, by which provision the link is swingable vertically on the clevis and capable of limited endwise movement in the opening 16. At opposite sides of the clevis 8 the arms of the bail-like extension 14 are formed with integral guide flanges or collars 17 which prevent independent lateral movement of the clevis 8 and link 12. The link 12 is slidably supported on a transverse bearing plate 18 which is extended across the top of the draft extension 1 at the forward end thereof.

The thickness of the bearing plate 18 and the relative position of the slotted opening 16 of the clevis 8 above the top of the draft extension 1 is such that the coupling link 12 is normally maintained in a horizontal position at an ample elevation to readily pass over the top of the adjoining draft extension 2 of the car to be coupled. Located on the draft extension 2 at the outer end thereof and in alignment with the longitudinal axis of the assembled coupler elements on the draft extension 1, is an upstanding coupling lug 19 having longitudinal base flanges 20 at opposite sides thereof which are bolted to the draft extension 2, as at 21. The top of the lug 19 is beveled, being inclined continuously upwardly and rearwardly from its forward end which is coincident with the plane of the top face of the draft extension 2 to its inner end which is in a plane considerably higher than that of the top of the extension 2. By this form and arrangement of the lug 19 the coupling of the two cars is automatically effected as they are brought together, because the rounded enlargement 13 of the link 12 engages the inclined top face of the lug 19, rides upwardly thereover and drops behind the lug and thereby prevents separation of the coupled cars until the link 12 is lifted from its engaging relation to the lug 19.

Partially surrounding the lug 19 at opposite sides and rearwardly thereof, are upstanding arcuate guide members 23, said members 23, as shown, having base flanges 24 which are bolted to the draft extension 2, as at 25, the top edges

of said members 23 being in a plane somewhat higher than the inner end portion of the coupling lug 19 and the general arrangement and location of said members 23 being such that they serve to receive, guide and center the enlarged ring portion 13 of the link 12 and cause the latter to readily engage over said lug 19.

To retain the circular enlargement 13 of the coupling link 12 in its coupled relation to the coupling lug 19, a special latch element 26 is provided. As shown, this latch element is formed of a single rod section or piece of heavy wire which is peculiarly formed by being bent first into substantially U-shape, producing parallel horizontal elongated leg portions 27 which are connected by a straight cross member 28, said leg portions 27 being rebent at an acute angle, as at 29, and formed with eyes 30 at their extreme ends by which the latch member is pivotally mounted as will presently more fully appear.

The support for the latch element 26, as shown, includes a removable rectangular block 31 which is fitted between the upper portions of side plates 32 of a channeled standard 33 having base flanges 34 which are bolted, as at 35, on top of the draft extension 2 some distance inward from the coupling lug 19. The open vertical side of the standard 33 is disposed toward the coupling lug 19 and the bottom end opening of the standard is in communication with a longitudinally elongated slot 36 provided in the draft extension 2 and extending from the rear vertical wall of the standard to the inner end of the draft lug 19 (see Figure 2). The removable supporting block 31, which, in addition to affording a part of the support for the latch element 26, is in effect a body filler and cross support for the upper portions of the side plates 32 of the standard 33 and is held in place by a pivot bolt 37 for the latch element 26 and a supplemental tie bolt 38, the latter being inserted only through registered apertures in the side plates 32 and the block 31 and directly clamping the side plates to the block, while the bolt 37 is somewhat longer than the bolt 38 to hingedly receive thereon, outside the side plates 32, the eye portions 30 of the angular portions 29 of the latch element.

The block 31 terminates with its lower end in a plane slightly above that of the inner end of the coupling lug 19 and its inner vertical side is spaced from the inner vertical wall of the standard 33, the vertical spacing providing a slideway for a latch-operator 39 comprising a body shank of rectangular cross section and having a right-angular foot extension 40 at its lower end, said extension being normally positioned within the slot 36 of the draft extension 2 with its forward end contiguous to the inner end of the coupling lug 19. The shank portion 39 is provided with a horizontal lug 41 which is projected through a vertical slot provided therefor in the adjacent inner wall portion of the standard.

In the normal lowered position of the latch-operator said lug 41 rests on the edge portion of the inner wall of the standard 33 at the bottom of the vertical slot provided in said wall, in which position of the latch-operator the intermediate cross member of the latch element rests on said lug 41 so that the parallel leg portions 27 of the latch element straddling the standard 33 are in a horizontal plane and the rebent angular portions 29 of the latch element are inclined between the pivot bolt or stud 37 and the inner end of the coupling lug 19 at the same angle and flush with the inclined top face of said lug 19.

In this connection, it is noted that while due to the proportionate leverage and weight of the intermediate portion of the latch element rearward of the pivotal axis of the latch element the latter is gravitated to the normal position shown in full lines in Figure 2, the coupling link 12 is much heavier than the overbalancing portion of said latch element whereby, when the coupling link 12 moves upwardly on the coupling lug 19 and onto the forward portion of said latch element, said forward portion swings downwardly under the weight of the coupling link so that the ring portion 13 of the link drops to a horizontal position as shown in full lines in Figure 2 and surrounds the coupling lug 19, whereupon the latch element is restored to its normal position with its forward end portion overhanging the ring portion 13 of the coupling link 12 and prevents the swinging of the coupling link out of engaging relation to said coupling lug 19 until such time that the latch-operator 39 is lifted to swing the latch element out of the way and simultaneously lift the coupling link 12 sufficiently for the ring portion 13 of the link to clear the top of the coupling lug 19.

The lifting of the latch-operator 39 is effected by means of a crank arm 42 having a pivotal link connection 43 with the upper end portion of the body shank of said latch-operator, said crank arm 42 being an integral extension of a shaft 44 rotatably mounted, as at 45, on the adjacent end portion of the car body and provided at its opposite end with an operating handle 46. The foot portion 40 of the latch-operator 39 being located normally some distance below the overhanging ring portion 13 of the coupling link 12 the latch-operator in its upward movement first causes a downward swinging movement of the forward portion of the latch element 26 before the foot portion 40 of the operator moves into engagement with the ring portion 13 of the coupling link, due to the direct engagement of the transverse intermediate portion 28 of the latch element with the lug 41 of the body shank of the latch-operator, the relative proportions of the parts and the spacing therebetween being such that the forward portion of the latch element is swung downwardly and rearwardly clear of the ring portion 13 of the coupling link 12 so that the continued upward movement of the latch-operator 39 with the foot portion 40 engaging under the ring portion 13 of the link 12 raises the link swingably on the clevis 8 to an elevation where it is clear of the inner end portion of the coupling lug 19 sufficient to permit the separation of the cars. After the cars have been thus uncoupled the latch-operator 39 is permitted to drop to its normal position, whereupon the latch element moves therewith to its normal position.

While the structure herein illustrated and described is a practical embodiment of the invention it is obvious that considerable modification may be made therein without departing from the spirit of the invention as defined in the appended claims. The invention, therefore, is not limited to the specific construction and arrangement shown.

What is claimed is:

1. In a car coupling of the character described, in combination with meeting draft extensions of two cars to be coupled, a coupling link pivotally mounted at its inner end portion on the one draft extension with provision for unlimited vertical swinging movement but limited lateral swinging movement and also with limited end-

wise movement, means on said draft extension for slidably supporting said coupling link substantially horizontally in a plane above the top of the draft extension, an upstanding coupling lug rigidly secured on the other draft extension adjacent the outer end thereof and in alinement with the normal longitudinal axis of the coupling link on said first mentioned draft extension, said coupling lug having a top face inclining upwardly and rearwardly from a plane coincident with the top of said other draft extension to a higher plane at the inner end of the lug, forwardly flared link-guiding members at opposite sides of said coupling lug, a longitudinally alined standard of channel section secured on said other draft extension inwardly from said coupling lug, the open side of the standard being disposed toward the coupling lug, a latch element comprising a single rod section bent intermediate its ends into a form substantially U-shaped to straddle the standard, thence rebent at an acute angle at the ends of the legs of the U-shaped portion and formed with eyes at the extreme ends of the element, a pivot bolt mounted on said standard transversely thereon of on which the eye portions of the latch element are rotatably mounted, a latch-operator slidably mounted for vertical movement on said standard, said latch-operator having a forwardly extending foot portion normally positioned in an opening in said other draft extension and in a horizontal plane below the top of said extension, said foot portion terminating coincident with a vertical plane adjacent the inner end of said coupling lug whereby to underlie the coupling link when the latter is in coupled relation to said coupling lug, said latch-operator having a lateral lug at an elevation above said foot portion thereof for normally supporting the intermediate portion of the latch element in correlation to the pivotal support of said element with the corner portions where the element is rebent inclinedly located contiguous to the upper inner end portion of said coupling lug, and manually operable means for lifting said latch-operator to move the forward portion of the latch element downwardly and rearwardly on its pivot out of the range of the coupling link in the coupled relation of the link to said coupling lug and to lift the link clear of

the lug during such movement of the latch element.

2. In a car coupling of the character described, in combination with meeting draft extensions of two cars to be coupled, a supporting bracket mounted on the one draft extension, a clevis having a shank portion pivotally attached to said supporting bracket whereby to swing with limited movement horizontally about a vertical axis, a coupling link hingedly mounted at its rear portion on said clevis whereby to swing laterally with the clevis but to swing vertically about a horizontal axis independently of the clevis, said link having a circular forward body portion, means fixed on the draft extension forward of the clevis supporting bracket and on which the coupling link is normally supported substantially horizontally but slidably so as to swing laterally with the clevis in a plane above the top of the draft extension, an upstanding coupling lug on the other draft extension adjacent the outer end thereof and in alinement with the normal longitudinal axis of the clevis and attached coupling link on said first-mentioned draft extension, said coupling lug having an inclined longitudinal top face, upstanding forwardly flared guide members partially surrounding said coupling lug in spaced relation thereto at opposite sides and rearwardly thereof, a latch element hingedely mounted on a support inwardly from said coupling lug and having a downwardly swingable forwardly extended body portion normally spanning the space between its support and the lug with its forward end portion contiguous to the upper inner end portion of the lug and being held against bodily movement upward from its normal position, said forwardly extended body portion of the latch element being overbalanced and depressed by the weight of the coupling link moving thereon from the inclined top face of the coupling lug and into coupled relation to the lug, and means for manually actuating the latch element to move its forwardly extended body portion downwardly out of the range of the coupling link in the coupled relation of the link to the coupling lug and lifting the link to clear the lug during such movement of the latch element.

CHURCH G. HUMPHREYS.
